1,991,453

FLUID DISTRIBUTOR FOR HYDRAULIC JACKS

Jean Albert Giovannoni, Lille, France

Application December 8, 1933, Serial No. 701,553
In Germany December 27, 1932

4 Claims. (Cl. 60—52)

The present invention relates to hydraulic jacks or similar fluid-actuated lifting appliances and has more particular reference to the distributors or valve systems used for forcing the fluid from a reserve chamber to the cylinder containing the reciprocatable jack piston for actuating it and lifting the load or for allowing the fluid to return to said reserve chamber when the pressure of the jack must be released.

10 The primary object of the invention is to provide an improved fluid distributor for hydraulic jacks or the like wherein the fluid from the reserve chamber flowing to the jack piston cylinder and the fluid from said cylinder flowing back to said chamber follow the same path from or towards the reserve chamber owing to a mere flow reversal placed under the operator's control, whereby a double path and concomitant duplicated piping is avoided, which results in a lesser 15 volume, lesser number of parts and cheaper cost of the apparatus.

A further object of the invention is to provide an improved fluid distributor of the aforesaid type wherein the reversal of the flow of the actuating fluid is performed by extremely simple means with the aid of valves distributed along said path in a sequence of communicating chambers and requiring no springs since their application upon, or release from, their seats is performed automatically by the mere drag of the 20 fluid upon them.

A still further object of the invention is to provide an improved fluid distributor of the aforesaid type wherein no special or extraneous braking contrivance is necessitated for slackening the rate at which the lifting or jacking piston comes down when the fluid pressure is released, the braking action taking place automatically owing to the novel arrangement and operation of very 25 simple throttling means in the fluid path, as soon as said rate of descent exceeds a predetermined value, which obviates any danger of the load sinking too fast.

Still a further object of the invention is to provide an improved fluid distributor for hydraulic jacks or the like of extremely simple and rugged structure capable of ensuring a perfect operation even in the long run and of being manufactured or kept up at relatively low cost.

30 With these and such other objects in view as will incidentally appear hereinafter, the invention comprises the novel arrangement and disposition of parts that will now be described with reference to the accompanying diagrammatic drawings forming a part of the present disclosure

and illustrating by way of example a suitable embodiment of the invention.

In the drawings:

Figure 1 is a fragmentary elevational view partly in section of a hydraulic jack fitted with the improved fluid distributor according to the invention, this distributor being shown on the right hand side of the figure.

Figure 2 is a diagrammatic view illustrating the fluid distributor, on an enlarged scale, assuming the fluid to flow into the control pump chamber to prime said pump.

Figure 3 is a view similar to Figure 2 assuming the fluid to continue to flow into the control pump cylinder.

Figure 4 is a view similar to Figure 2, assuming the piston of the control pump being depressed and the fluid therefrom being forced into the jack cylinder.

Figure 5 is another view similar to Figure 2, assuming the lifting piston in the jack cylinder coming down under the pressure of the load (not shown), the back flow of the fluid being throttled by a braking valve incorporated in the distributor.

Like reference characters designate like parts throughout the several views.

Reference being first had to Figure 1, A designates the actuating lever of the pump adapted to control the flow of fluid actuating the jack. This lever A is linked at B to a piston 1 accommodated in a distributor cylinder 3. Said lever is fulcrumed on an oscillatable link D.

E designates the cylindrical body of the jack hollowed to form a fluid chamber 11. F designates the lifting or jacking piston encircled at its upper end by packing rings G therefor and carrying a large nut H in which is threaded a set screw I. The lifting platform J on which the load to be jacked (not shown) may be located is supported by the top end of the lifting piston F. Adjacent the cylindrical body E of the jack is provided a reserve chamber 7 for a supply of fluid. At the bottom of said body E is arranged a leather cup L of known form held invariably in position by a grub screw M.

The fluid distributor is shown more clearly and on an enlarged scale in Figures 2 to 5. In the illustrated embodiment, the fluid distributor comprises primarily a pair of co-axial inter-communicating chambers 4, 5 located in vertical alignment with the control piston 1, to wit: a primary chamber 5 and a secondary chamber 4 connected by a side duct 2 to the pump cylinder 3. Through the primary chamber 5 passes

a tappet rod 16 slidably fitted through the upper wall of the distributor and having a flange-like enlargement 17 for a purpose that will be described hereafter. The primary chamber 5 is connected to the secondary chamber 4 by a free opening through the lower end of the tappet rod 16 can pass, and it is connected to the reserve chamber 7 containing the supply of fluid by a duct 6. Underneath the secondary chamber 4 is provided a third chamber 8 which freely communicates with said chamber 4 and with a further subjacent chamber 9 which for the sake of clearness, may be termed the fourth chamber. This chamber 9 is co-axial with the chambers 5, 4, 8 in the embodiment illustrated but this is not essential for a proper operation of the distributor. The fourth chamber 9 is connected by a duct 10 with the cylinder 11 formed in the jack body E in which the lifting piston F can reciprocate for jacking purposes.

In the chambers 4, 8, 9 are snugly arranged movable valves which, in the embodiment illustrated, are in the shape of ball valves 14, 13, 15 and are adapted to bear against corresponding seats formed by shoulders provided between these respective chambers which are of increasing cross-sectional area in the downward direction. The valves 14, 13, 15 located respectively in these chambers are similarly of progressively larger volume; they require no springs for being applied upon, or released from, their seats because their application onto, or release from, their seats is performed automatically by the flow of fluid in the one or the other direction, as will result from the following description. The seat between the chambers 8 and 9 for the lower valve 15 is chamfered or otherwise formed to provide throttle passages 18 for a purpose that will appear hereafter.

The operation of the fluid distributor is as follows:

As soon as the piston 1 is lifted in the control pump cylinder 3 by means of the actuating lever A, the suction generated in the secondary chamber 4 draws the valve 14 off its seat in the opening between the chambers 4 and 5 and permits the fluid sucked from the reserve chamber 7 to flow into the cylinder 3 through the duct 2. The control pump is thus primed. The valve 13 between the chambers 4 and 8 then remains applied upon its seat owing to the pressure head from the cylinder 11 in which the lifting piston F exerts its pressure. The fluid is then drawn through 6-5-2 into the control pump cylinder 3 while the piston 1 is further lifted, as shown in Figure 3. When however the piston 1 is afterwards depressed (see Fig. 4) the fluid is forced through the duct 2 and chamber 4, as a result of which the valve 14 is pushed up against its seat, which cuts off communication between the chambers 4 and 5 while pushing the valve 13 off its seat, whereby the fluid flows through the chambers 8 and 9 and along the duct 10 to the jack cylinder 11, and raises the lifting piston E. By further depressing the control piston 1 by means of the actuating lever A, said piston comes into contact with the tappet rod 16 engaged through the primary chamber 5, so that this rod pushes the valve 14 downwardly off its seat and re-establishes communication between the chambers 4 and 5. When thus pushed down the valve 14 contacts with the valve 13 and can thus push it off its seat. The fluid can thus flow back from the jack cylinder 11 through the duct 10 and chambers 9, 8, 4, 5

and through the return duct 6 to the reserve chamber 7 until the reverse cycle is resumed. However should this return flow of the fluid reach a certain intensity due to the action of a load on the platform J, the valve 15 is dragged against its seat, whereby the fluid can no longer flow from the chamber 9 to the chamber 8 freely but is slackened or braked by the throttle openings 18 which retard the rate of flow. The piston F supporting the load on the platform J (which load is not shown and may have any shape) is then prevented from coming down at an undue speed into the jack cylinder 11. Thus the descent of the lifting piston is automatically braked by throttling means incorporated into the structure of the distributor.

The return flow of the fluid from the cylinder 11 to the reserve chamber 7 is checked or braked by the position of the enlargement 17 on the tappet rod 16 opposite the duct 6, as shown in Figure 5. The position and size of said enlargement are so arranged that it throttles the flow of fluid from the secondary or middle chamber 4 to the duct 6 and through the fore or primary chamber 5 even before the parts of the distributor occupy the respective positions shown in Figure 5 i. e. before the valve 15 has been applied upon its seat. The position of the enlargement 17 is so arranged that it causes braking action to take place before the valve 15 is dragged upon its seat by the flow of fluid from the fourth chamber 9 to the tertiary chamber 8.

It will be appreciated from the foregoing description that the objects of the invention are satisfactorily met by the improved fluid distributor since the operation of the pressure-responsive valves 14 and 13 located in the secondary and tertiary chambers 4 and 8 respectively is fully automatic under the flow of the fluid in the one or the other direction and under the timely action of the tappet rod 16 responsive to the actuation of the piston 1, while the valve 15 also functions automatically to cause the return flow of fluid to be throttled through the narrow passages 18 as soon as said last-named valve is applied on its seat by a fluid flow of predetermined intensity.

Numerous constructional details of the structure might of course be changed without departing from the scope of the subjoined claims.

What I claim is:

1. In combination with a hydraulic jack having a control pump connected with the fluid supply and with the jack cylinder, a fluid distributor comprising in co-axial alignment a primary chamber connected to the said supply, a secondary chamber interconnected to the primary chamber and control pump, and a tertiary chamber interconnected to the secondary chamber and jack cylinder, pressure-responsive valves freely reciprocable respectively in the secondary and third chambers to or from seats in said chambers for permitting a flow of fluid from the supply to the control pump during the suction stroke of the control piston and from said pump to said cylinder during its forcing stroke, the valve in the secondary chamber being capable of contacting with the valve in the third chamber when unseated, means in the primary chamber for unseating the valve in the secondary chamber responsive to said forcing stroke and then for causing the last named valve to unseat the valve in the third chamber when said forcing stroke is increased, and throttling means between the tertiary chamber and jack cylinder, said last-

named means being actuatable when said return flow reaches a predetermined intensity.

2. In combination with a hydraulic jack having a control pump connected with the fluid supply and with the jack cylinder, a fluid distributor comprising in co-axial vertical alignment a primary chamber connected to the said supply, a secondary chamber interconnected to the primary chamber and control pump, and a tertiary chamber interconnected to the secondary chamber and jack cylinder, pressure-responsive valves freely reciprocable respectively in the secondary and third chambers to or from seats in said chambers for allowing a flow of fluid from the supply to the control pump during the suction stroke of the control piston and from said pump to said cylinder during its forcing stroke, the valve in the secondary chamber being capable of contacting with the valve in the third chamber when unseated, a tappet rod movable through the control pump and primary chamber and having an enlargement for throttling the fluid return flow from jack cylinder to supply responsive to said forcing stroke while unseating the valve in the secondary chamber and then causing the last named valve to unseat the valve in the third chamber when said forcing stroke is increased, and throttling means between the tertiary chamber and jack cylinder, said means being actuatable when said return flow reaches a predetermined intensity.

3. In combination with a hydraulic jack having a control pump connected with the fluid supply and with the jack cylinder, a fluid distributor comprising in co-axial vertical alignment a primary chamber connected to the said supply, a secondary chamber interconnected to the primary chamber and control pump, and a tertiary chamber interconnected to the secondary chamber and jack cylinder, pressure-influenced valves freely reciprocable respectively in the secondary and tertiary chambers to or from seats in said chambers responsive to the direction of the fluid flow for allowing a flow from supply to control pump during the suction stroke of the control piston and a reverse flow from said pump to said cylinder during its forcing stroke, the valve in the secondary chamber being capable of contacting with the valve in the third chamber when unseated, tappet means in the primary chamber co-related

to the action of the control piston for unseating the valve in the secondary chamber while throttling the fluid return flow from jack cylinder to supply responsive to said forcing stroke and while causing the last-named valve to unseat the valve in the third chamber when said forcing stroke is increased, and a quaternary chamber located between the tertiary chamber and jack cylinder and containing a return flow-actuated valve, the seat for this valve having narrow passages for throttling the flow of fluid when the last-named valve is applied to its seat by a predetermined intensity of said return flow.

4. In combination with a hydraulic jack having a control pump connected with the fluid supply and with the jack cylinder, a fluid distributor comprising in co-axial vertical alignment a primary chamber connected to said supply, a secondary chamber interconnected to the primary chamber and control pump, and a tertiary chamber interconnected to the secondary chamber and jack cylinder, said chambers being of increasing cross section to provide shoulders, pressure-urged ball valves freely reciprocable to or from said seat-like shoulders responsive to the direction of the fluid flow so as to allow a flow from supply to pump during the suction stroke of the control piston and a reverse flow from pump to jack cylinder during the forcing stroke of said piston, the valve in the secondary chamber being capable of contacting with the valve in the third chamber when unseated, a tappet rod slidable through the primary chamber and projecting into the pump for being co-related to the piston motions for unseating the valve in the secondary chamber responsive to the forcing stroke of the piston and for causing the last named valve to unseat the valve in the third chamber when said forcing stroke is increased, said rod having an enlargement for throttling the fluid return flow during the last-named stroke, and a quaternary chamber located between the tertiary chamber and jack cylinder and containing a return flow-actuated valve, the seat for this valve having throttling passages for checking the return flow of fluid when the last-named valve is dragged upon its seat by a predetermined intensity of said return flow.

JEAN ALBERT GIOVANNONI. 50
